FOLDED BLANK BOX

Filed Sept. 13, 1927

2 Sheets-Sheet 2

UNITED STATES PATENT OFFICE.

CLOUD D. HUGHES, OF KENNEDY SQUARE, PENNSYLVANIA.

FOLDED BLANK BOX.

Application filed September 13, 1927. Serial No. 219,322.

This invention relates particularly to multi-compartment shipping containers or what might be termed a multiple box unit composed of strong more or less flexible sheet material produced in flat blank form capable of being folded up to produce the shipping container forming the several boxes or compartments; and the objects and nature of the invention will be readily understood by those skilled in the art in the light of the following description of the accompanying drawings illustrating what I now believe to be the preferred mechanical expression or embodiment of my invention from among other forms and constructions within the spirit and scope thereof.

A particular object of my invention is to provide an improved multiple box unit capable of being formed from a single sheet material blank and particularly intended for packing and shipping various products and of such strength and durability as to be capable of use, in the field for instance, by pickers of berries or other products or mushrooms and capable of being closed for shipment and also capable of being readily separated into separate individually complete boxes or containers.

With this and other objects in view my invention consists in certain novel features of construction and in formations and arrangements as more fully and particularly described and specified hereinafter.

Referring to the accompanying drawings forming a part hereof:

Fig. 1 shows in perspective the multiple box unit embodying my invention, and this embodiment consisting of two approximately similar compartments or boxes shown with top covers or closing flaps in closed position.

Fig. 2 is a vertical longitudinal section taken on line 2—2, Fig. 1.

Fig. 3 shows one of the boxes or individually complete compartments separated from the other.

Fig. 4 diagrammatically illustrates in plan view a form of flat sheet material blank capable of being bent and folded to form the complete multiple box unit of Fig. 1.

The complete multiple box unit of Fig. 1 consists of two approximately similar or duplicate boxes or compartments arranged end to end and open at the top and each provided with its own top closure or flap.

These two boxes are joined together by a

flat bottom which is continuous from box to box and by upright side walls continuous from box to box, and this bottom and these side walls are capable of being severed in a common vertical plane, say along the line 60 *f*, to separate the two individually complete boxes.

These two approximately duplicate individually complete boxes, are each formed with its own side and end walls, its own bottom wall and its own top closing flap or closure.

The inner end wall of each box is approximately of duplicate thickness and is tied to the opposite side walls and to the opposite 70 end wall and the opposite side walls are of double thickness.

This structure is attained and these results are accomplished, by providing a single flat blank capable of being folded and bent 75 to constitute the two box unit, such a two box unit as is capable of being divided or severed into two individually complete boxes each of a capacity equal to approximately one-half the capacity of the complete multiple box unit.

For instance, in Fig. 4 I show a diagram of this flat blank which provides a central longitudinally elongated body length substantially oblong in form when the edges 85 thereof are defined by the longitudinal lines *a*, *b*. This body length is in one piece or continuous from end to end to form the bottoms 1, 1^a, of the two boxes, the outer vertical end walls 2, 2^a of the two boxes and 90 the top covers or closure flaps 3, 3^a, of the two boxes.

At its central portion this blank is formed with the similar opposite flaps 4, 4^a, and 4, 4^a, capable of being bent to vertical position on the fold lines *a*, *b*, to form upright side walls for the two boxes rising from the bottoms 1, 1^a, of the two boxes. These pairs of side walls 4, 4^a, are continuous from box to box except for the notches 5 depending 95 through the top edges of said pairs of walls 4, 4^a for a short distance, and defining the side walls 4 of one box from the side walls 4^a of the other box.

Between said side wall forming flaps 4, 105 4^a of the blank and the cover flaps 3, 3^a of the blank, are arranged two similar pairs of elongated flaps that project laterally from opposite ends of the panels 2, of the body of the blank. For instance, two elongated 110

tongues or flaps extend in opposite directions in continuation of the panel 2 to form two panels 6 and two free end panels 7. A similar arrangement is provided of flaps or 5 tongues extending in opposite directions from the opposite ends of the panel 2^a, to provide two similar panels 6^a and two similar end panels 7^a.

After the two sets of similar side walls 10 4, 4^a, are bent to vertical position, the panel 2 is bent to upright position on the transverse fold line *e*, so as to rise vertically from the bottom forming panel 1, 1^a. The panels 15 6 are then folded inwardly on the fold lines *a*, *b*, so that the panels 6 close inwardly against the outer vertical surfaces of the upright walls 4, and while this operation is being performed the notches 9 are entered into the notches 5, and the panels 7 are bent 20 inwardly on the fold lines *c*, so that the two opposite panels 7 will lap one over the other and extend across the space over the bottom panel 1 and between the two pairs of upright walls 4, 4^a, to form the inner end 25 wall of the compartment or individual box having the bottom 1 and the outer end wall 2. These two flap ends or panels 7 are notched or slit at 8 in opposite directions so that they can interlock as more clearly 30 indicated by Fig. 3 to form the inner end wall of the box and to tie together the panels 6 forming the outer layers of the side walls of the box.

In this connection it will be noted that the 35 box side walls are double in that the inner layers thereof are formed by the wall portions 4 and the outer layers thereof are formed by the panels 6 that constitute end continuations of the panel 2 that forms the 40 outer end wall of this box.

The other box of the multiple unit, the bottom of which is formed by the panel 1^a has its outer end wall formed by bending up the panel 2^a on the fold line *e* to vertical 45 position, and then bending the panels 6^a on the fold lines *a*, *b*, against the outer sides of the upright side wall portions 4^a, and then bending the end flaps or end panels 7^a on the line *c* and inserting the notches 9^a in 50 the notches 5 and interlocking the two end panels 7^a by means of the slits 8^a to form the inner end wall of the other compartment, namely, the compartment having its bottom formed by panel 1^a, as heretofore 55 described in connection with the formation of the other box of the multiple unit.

When these boxes of the multiple unit are formed, as so far described, we have two boxes built up on an unbroken portion, 1, 1^a, 60 of the blank that forms the bottoms of both boxes with the two boxes arranged end to end. These two boxes are open at the top and can be most conveniently employed by pickers in the field in filling the boxes with 65 the product to be shipped.

When the boxes have received the desired quantity of the material to be shipped, the cover flaps, 3, 3^a, forming upward and outward continuations of the outer end walls 2, 2^a, of the two boxes, can then be folded 70 upwardly and downwardly over their respective boxes to cover the same.

These cover flaps 3, 3^a, are preferably formed with side flaps 30, 30^a, having projecting portions forming tongues 31, 31^a, to 75 close down at the sides of their respective boxes so that the tongues can enter slots 10, 10^a, in the outer wall forming panels 6, 6^a, to maintain the covers in closed positions.

It will be noted, that the multiple box unit 80 is braced or trussed and stiffened against bending or buckling vertically, particularly on a transverse line located between the two individual boxes, by the channel bar or flanged formation of the blank between and 85 joining the two boxes. This formation is attained by providing the body portion of the sheet blank continuous from box bottom panel 1, to box bottom panel 1^a, with the pairs of vertical flanges or walls 4, 4^a, rising 90 from opposite edges of both said panels and continuous from panel or wall portion 4, of one box to panel or wall portion 4^a, of the other box, except for the short notches 5. The notches 5, permit anchoring the respective 95 boxes to the two pairs of vertical walls, through the medium of the two pairs of long lateral tongues or flaps 6^a, 7^a and 6, 7, integral with the body panels 2^a, 2, that form the outer end walls of the two boxes.

The blanks can be sent to the field or to the packers in flat form, and can be folded to operative box form by the pickers and/or packers, and can be carried and filled as the products are picked or gathered. This 100 is possible because of the trussed and braced formation of the multiple unit box when folded to form and because of the anchored and braced formation of each box.

The side flanges 30, or 30^a, of the cover 110 flaps 3, 3^a, in the preferred form as shown extend down at the outer surfaces of the outer side wall layers 6, 6^a, of the boxes with the locking tongues 31, 31^a, entering the slots 10, from the outside, so that the cover is supported on and against the double walls with whatever weight or forces may be applied thereto and thereon. However, as an alternative and where desired said cover flanges 30, 30^a, can be slipped down between the 115 inner layers 4, or 4^a, and the outer layers 6, or 6^a, of the box side walls with tongues 31, 31^a, projecting outwardly through slots 10, to the exterior of the boxes.

The two boxes can be of uniform capacity, 120 each to carry, say a pound and a half of mushrooms, thus the multiple box unit will contain, say three pounds of mushrooms. Where the retailer has an order for a pound and a half of mushrooms or other product, 125

he can subdivide the multiple box unit by transversely severing the same along the dotted line *f*, thus producing two separate individually complete and covered boxes 5 containing the desired quantity of product. By severing the body of the blank transversely across its center along line *f*, the two box bottoms 1, 1^a, and the two box end walls 4, 4^a, are separated, between and without disturbing the inner end wall 7, of one 10 box or the inner end wall 7^a, of the other box.

Various changes, departures and modifications can be resorted to without departing 15 from the spirit and scope of the invention and hence I do not wish to limit my invention to the substantially exact embodiment disclosed.

What I claim is:—

20 1. A flat sheet material blank for a multiple box unit, having a central longitudinal body length foldable to form the bottoms, outer end walls and top closure flaps of the several boxes of the unit, a pair of opposite flaps extending laterally from said body length to bend up and form side wall portions of the several boxes and pairs of opposite elongated tongues extending laterally from said body length to face said side 25 wall portions and form inner end walls of the several boxes.

2. A flat sheet material blank formed to fold to form a multiple box unit, said blank having a central body length foldable to 30 form a continuous bottom for two boxes and the outer end walls thereof, said length at its central portion having two opposite flaps to fold up from said continuous bottom and form connected side wall portions of said 35 two boxes, said length also having opposite pairs of tongues extending laterally from its outer end wall forming portions, respectively, and constructed and formed to face said side wall portions of the boxes and interlock therewith and form the inner end 40 walls of the boxes.

3. A flat sheet material blank formed to bend and fold to provide a multiple box unit, said blank providing a body length 45 providing a bottom for two boxes of said unit and the outer end walls of said boxes and top closure flaps for said boxes, said body length having notched side flaps to bend up from said bottom, and also having 50 tongues extending from opposite edges of said outer end wall portions to extend there-

from along the outer faces of said bent up side flaps and inwardly through said notches therein and transversely across said bottom to form the separate inner end walls of said 60 two boxes, the tongue ends of each inner end wall formed to be secured together.

4. A flat sheet blank constructed to fold and interlock to form a multiple box unit, said blank having an elongated body portion providing a central panel to form the bottoms of two boxes, and panels to form the outer end walls of the two boxes, said central panel having two opposite edge flaps, each centrally notched to bend up and 65 form side wall portions of the two boxes, each box end wall panel having two opposite edge tongues forming side wall panels and inner end wall panels, said tongues notched to traverse and interlock with the notched 70 portions of said side wall flaps, the free ends of said tongues formed to overlap and secure together between the side wall flaps and over said bottom forming central panel, said central panel and said side wall flaps 75 formed and arranged to be transversely severed to separate the unit into two individually complete boxes.

5. A two box unit folded up from a single flat sheet blank and formed thereby, said 80 unit embodying two individually complete open-top boxes, the bottoms of said two boxes formed by a continuous panel of said box, the opposite vertical side walls of said two boxes embodying two continuous flaps bent 85 up from said panel, whereby said panel and said flaps can be transversely severed to separate the unit into two boxes.

6. A two box unit folded up from a single flat sheet blank, said unit embodying two 90 individually complete open-top boxes, the bottoms of said two boxes formed by a continuous panel of said blank, the opposite vertical side walls of said two boxes embodying two continuous panels bent up from 95 said bottom forming panel, and the vertical inner end walls of said boxes each embodying interlocking flaps bent up from said blank and extending across said bottom panel between said opposite side walls, whereby 100 said bottom panel and opposite side walls can be transversely severed between said inner end walls to separate the unit into two boxes.

Signed at Kennett Square, Pennsylvania, this 7th day of September, 1927.

CLOUD D. HUGHES.
